UNITED STATES PATENT OFFICE.

ROY G. HOFFERT, OF RACINE, WISCONSIN, ASSIGNOR TO THE CHRISTENSEN MACHINE CO., OF RACINE, WISCONSIN, A CORPORATION OF WISCONSIN.

SIGNATURE-STITCHING MACHINE.

Application filed July 31, 1924. Serial No. 729,350.

This invention relates to certain new and useful improvements in signature stitching machines and refers more particularly to that type of machine wherein the signatures are collected in groups or gangs by a continuous conveyor and fed to stitching mechanism to be bound in completed books or pamphlets.

In Letters Patent No. 1,360,886, granted November 30, 1920, to Martin Christensen, is illustrated an improved device for use in connection with signature stitching machines to facilitate the convenient handling of what is termed in the art as extension cover work, wherein the collected groups or gangs of signatures are properly presented to the stitching mechanism with their covers so positioned as to have the edges thereof extended beyond the edges of the signatures, and it is one of the objects of this invention to provide means cooperating with extended cover pusher members whereby the signatures and covers are deposited on the conveyor in engagement with the proper portions of the pusher members.

In experience it has been found necessary to employ considerable diligence in the placing of extension covers on the conveyor to insure their engagement with the extension cover face or portion of the pusher members and, as a result it has been found necessary to place the covers on the conveyor by hand, materially slowing down the machine.

It is, therefore, another object of this invention to provide an improved type of station or supporting means mounted above the continuous conveyor on which the signatures and covers are placed and so held with relation to the conveyor as to insure the engagement of the signatures with the signature engaging face of the pusher members and the engagement of the covers with the cover engaging face of the pusher members to insure their presentation to the stitching mechanism with the cover edges extended beyond the edges of the signatures the desired distance.

A further object of this invention resides in the provision of signature collecting and conveying means which will permit the operation of the stitching machine at high rate of speed in connection with extension cover work as well as the ordinary type of work.

This invention contemplates as a still further object the provision of adjustable members for the conveyor pusher members which are made from a single length of material to permit their quantity production at a comparatively low cost.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a perspective view of a portion of the endless conveyor of a signature stitching machine equipped with my invention;

Figure 2 is a top plan view of the innermost or cover supporting means or station upon which the covers are deposited to be deposited on the previously collected groups or gangs of signatures being conveyed by one of the pusher members;

Figure 3 is a view, partly in transverse section and partly in elevation, taken through the conveyor on the plane of the line 3-3 of Figure 1;

Figure 4 is a view similar to Figure 3 taken through the conveyor chain at another point on the plane of the line 4-4 of Figure 1, and

Figure 5 is a view similar to Figure 4 taken through Figure 2 on the plane of the line 5-5.

Referring now more particularly to the accompanying drawings, in which like numerals designate like parts throughout the several views, the numeral 5 designates a guide member for supporting the upper stretch of an endless signature conveyor 6, the guide member being supported at intervals by suitable standards 7. Conveyor 6 is preferably formed of a plurality of connected inverted V-shaped members to provide what is termed in the art as a saddle.

conveyor, and the lower stretch thereof is protected by a guard housing 8 suitably supported from the standards 7.

As is well known in the art, the inner end 5 of the endless conveyor terminates adjacent means for picking up the collected gangs or groups of signatures and advancing them to suitable stitching mechanism, not shown, from whence they are conveyed and discharged 10 in the form of completed books. While the conveyor 6 is described as being of the continuously operated type it will be understood that the same may be of the intermittent type adapted to convey the collected 15 groups or gangs of signatures directly to the stitching mechanism.

The conveyor chain is provided at intervals with pusher members 9 and, in the present embodiment, each member 9, comprises a 20 substantially U-shaped member adapted to be inserted through registered openings in the sides of the members forming the conveyor 6 with its outer ends or arms equally extended beyond the opposite sides thereof. 25 An adjustable member 10 is carried by each extended end or arm and has an offset face 11 for engaging the rear edges of the groups or gangs of signatures 12, the covers 13 engaging the ends of the pushing members 9. 30 above the members 10 to thus position the edges thereof beyond the edges of the signatures a distance equal to that between the offset portions 11 and the ends of the members 9.

35 As clearly illustrated in the drawings, the members 10 are bent from a single length of material and have a straight shank portion 14 which passes through an aperture in the pusher members and are adjustably secured 40 therein by set screws 15, the outer ends of the shank portions being folded, as at 16, and then directed laterally to provide the offset portions 11.

45 As will be readily obvious, the members 10 are secured in the pusher members with their offset portions 11 equally spaced therefrom in accordance with the degree it is desired to have the cover 13 extend beyond the signatures 12. This adjustment is quickly 50 effected by the loosening of set screws 15, adjusting the members 10 and tightening the set screws.

It is customary to provide stations or supporting means mounted above the conveyor, 55 and positioned at varying intervals, on which the signatures are placed and engaged by the pusher members as they pass therebeneath and removed from the stations onto the conveyor chain, the outer-most signature 60 or cover being deposited on the innermost station, the next signature on the second station and so on down in order that the signatures may be collected in their proper sequence and presented to the stitching mechanism, not shown, in the form of completed 65

gangs or groups ready to be stitched as previously described.

In practice it has been found that while the stations work highly satisfactory where extended cover work is not being handled, 70 they are unsatisfactory when extended cover work is being handled in that the signatures and covers are not, at all times, engaged with the proper portions of the extension cover pusher members. As a result, it has been 75 necessary in the past to place the signatures and covers on the conveyor by hand, materially reducing the speed of the machine and increasing the cost of handling the work. In the invention illustrated in the accompanying drawings, this difficulty is overcome 80 and the signatures and covers deposited on the stations without regard to whether extension cover work or conventional type of work is being handled without decreasing 85 the speed of the machine.

Extended upwardly from the standards 7 are station supports 17, the upper ends 18 of which terminate adjacent the upper stretch of the conveyor and carry trunnions 90 or bosses 19 from which the signature supporting means or stations 20 and 21 are mounted. The cover station 20 is supported from the inner-most support 17 and the signature stations 21 are supported from the other support 17. As will be readily apparent, there is but one cover station and as many signature stations as the length of the conveyor 6, and consequently the capacity of the machine, will accommodate. 100

The station 20 is in the form of an angular member 22 positioned above the conveyor in longitudinal alignment therewith and inverted to be partially telescoped thereover. The member 22 is mounted by suitably securing the outer end thereof to a supporting head 23 which is removably fixed on the trunnion or boss 19 of the inner-most support 17 by a set screw 24. As best illustrated in Figures 4 and 5, the member 22 is 110 of a size so that when a cover 13 is positioned thereon the depending portions thereof flare outwardly beyond the adjustable members 10 so that the rear edges of the cover depending portions are engaged by the extended ends of the next pusher member outwardly of the adjustable members 10. The outer end 25 of the supporting head 23 is flared to permit free passage of the previously collected groups or gangs of 115 signatures thereunder. 120

Each station 21 is in the form of a rod or bar 26, the extreme outer end of which is slightly offset and removably secured in a carrying head 27 by a set screw 28, the carrying head being in turn removably secured to the boss 19 of its support 17 by a set screw 29. The extreme outer end portion of the bar 26 being offset permits the positioning of the bar close to and parallel with 125 130

the apex of the conveyor and that portion of the bar paralleling the conveyor is of inverted V-shape in transverse sections, as best illustrated in Figure 3 to support a signature 12 at the fold thereof. The signature supports 26 being of relatively small size and being positioned close to the conveyor 6 cause the depending portions of signatures supported therefrom to hang close to the conveyor in the path of the offset portion 11 of the members 10 which engage the rear edges thereof as the pusher members pass the bar 26, spacing the signatures from the pusher members the distance it is desired to have the covers extend thereover.

The support 22 of the station 20 is spaced from the conveyor 6 a distance slightly greater than the bars 26 of the stations 21 and with this construction it will be readily obvious that the operators need to only deposit the signatures and covers on their respective stations and the pusher members remove the same therefrom onto the conveyor with their edges spaced the desired degree.

What I claim as my invention is:

1. In a stitching machine having a conveyor carrying a pusher member, a leaf engaging member bent from a single length of material and having a part to be secured to the pusher member and an offset part normally spaced from the face of the pusher member, said offset part providing a leaf engaging surface and said pusher member providing an extension cover engaging face.

2. In a stitching machine having a conveyor carrying a pusher member, a leaf engaging member bent from a single length of material, a shank carried by the leaf engaging member, means adjustably securing the shank to the pusher member, and a laterally struck part carried by the leaf engaging member, the laterally struck part providing a leaf engaging face and the pusher member outwardly of the leaf engaging member providing an extension cover engaging face.

3. The combination with the conveyor mechanism of a book stitching machine having a pusher member carried thereby and provided with offset signature and cover engaging faces for conveying a signature and a cover with their adjacent edges spaced, of a plurality of supporting means disposed above the conveyor, one of said supporting means being adapted to have a signature deposited thereon with its depending portions close to the conveyor in the path of the signature engaging face of the pusher member as the same is carried past said supporting means by the conveyor, the pusher member removing the signature therefrom onto the conveyor, the other of said supporting means being adapted to support a cover above the conveyor with its depending portions out of the path of the signature engaging face of the pusher member

gaging face of the pusher member but in the path of the cover engaging face thereof to be moved thereby from the said supporting means onto the conveyor over the signature previously deposited thereon with its edges 79 extended beyond the edges of the signature.

4. The combination with the conveyor mechanism of a book stitching machine having a pusher member carried thereby and provided with offset signature and cover engaging faces for conveying a signature and a cover with their adjacent edges spaced, of a plurality of supporting means disposed above the conveyor, one of said supporting means being relatively narrow in transverse section and adapted to have a signature deposited thereon with its depending portions close to the conveyor in the path of the signature engaging face of the pusher member as the same is carried past said supporting means by the conveyor, said pusher member removing the signature therefrom onto the conveyor, the other of said supporting means being wider in transverse section than the first-mentioned supporting means and 80 adapted to support a cover above the conveyor with its depending portions out of the path of the signature engaging face of the pusher member as the same is carried past said supporting means by the conveyor, said pusher member removing the signature therefrom onto the conveyor, the other of said supporting means being wider in transverse section than the first-mentioned supporting means and 85 adapted to support a cover above the conveyor with its depending portions out of the path of the signature engaging face of the pusher member as the same is carried past said supporting means by the conveyor, said pusher member removing the signature therefrom onto the conveyor, the other of said supporting means being wider in transverse section than the first-mentioned supporting means and 90 adapted to support a cover above the conveyor with its depending portions out of the path of the signature engaging face of the pusher member as the same is carried past said supporting means by the conveyor, said pusher member removing the signature therefrom onto the conveyor, the other of said supporting means being wider in transverse section than the first-mentioned supporting means and 95 adapted to support a cover above the conveyor with its depending portions out of the path of the signature engaging face of the pusher member as the same is carried past said supporting means by the conveyor, said pusher member removing the signature therefrom onto the conveyor, the other of said supporting means being wider in transverse section than the first-mentioned supporting means and 100

5. The combination with the conveyor mechanism of a book stitching machine having a pusher member carried thereby and provided with offset signature and cover engaging faces for conveying a signature and a cover with their adjacent edges spaced, of a plurality of supporting means disposed above the conveyor, one of said supporting means being in the form of a bar of inverted V-shape in transverse section, means mounting said bar above the conveyor in 105 longitudinal alignment with the apex thereof and close thereto, said supporting means bar being adapted to have a signature deposited thereon with its depending portions close to the conveyor in the path of the 110 signature engaging face of the pusher member as the same is carried past said supporting means by the conveyor, said pusher member removing the signature therefrom onto the conveyor, the other of said supporting means including an angular bar of inverted V-shape, and means mounting the supporting means angular bar above the conveyor with its apex in longitudinal alignment with the apex of the conveyor, said angular bar supporting means being adapted to support a cover above the conveyor with its depending portions out of the path of the signature engaging face of the pusher member but arranged to be engaged by the cover 115 120 125 130

engaging face thereof to be moved thereby from the said supporting means onto the conveyor over the signature previously deposited thereon with its edges extended beyond the edges of the signature.

6. The combination with a book stitching machine and its conveyor mechanism having pusher members carried thereby provided with offset signature and cover engaging faces for conveying collected groups of signatures and covers with their adjacent edges spaced, of a plurality of supporting means disposed above the conveyor at intervals to form stations upon which signatures and covers are placed to be removed therefrom and deposited on the conveyor by the pusher members as they progress from station to station, the supporting means nearest the

stitching machine maintaining covers placed thereon in a spread condition whereby their rear edges engage the cover engaging faces of the approaching pusher member to insure the projection of the edges of the cover from the edges of the signatures with which the signature engaging faces of said pusher member are engaged, and the supporting means positioned above the conveyor outwardly of the cover station being adapted to support the signatures placed thereon in a manner to droop downwardly with their folds close to the conveyor mechanism in line for engagement with the signature engaging faces of the conveyor mechanism pusher members.

In testimony whereof I affix my signature.
ROY G. HOFFERT.
